UNITED STATES PATENT OFFICE.

VERNON A. CONKLIN, OF OCEAN GROVE, NEW JERSEY, ASSIGNEE OF ONE-HALF TO
HENRY A. WILSON, OF NEW YORK, N. Y.

MAILING DEVICE.

Application filed March 3, 1923. Serial No. 632,631.

To all whom it may concern:

Be it known that I, VERNON A. CONKLIN, a citizen of the United States, and a resident of Ocean Grove, in the county of Monmouth and State of New Jersey, have invented new and useful Improvements in Mailing Devices, of which the following is a full, clear, and exact description.

This invention relates to mailing devices and was primarily designed for use with registered mail.

It has been found that in forwarding registered mail, if no means is provided in conjunction with the registered mail for acknowledging the receipt of the same, the receiver often neglects to acknowledge its receipt. Such neglect often causes great inconvenience and unnecessary worry over the delivery of registered mail.

The general object of this invention is the provision of a cheap and simple mailing device for containing registered mail, provided with a return card which may be readily detached on the receipt of the registered mail and delivered to the letter carrier.

This object is accomplished by utilizing an envelope provided with a closing flap on which a card-receiving pocket may be mounted, forming a weakened line in the envelope flap across the mouth of said card-receiving pocket, cutting in the envelope flap adjacent the weakened line openings for allowing the gripping and withdrawal of a card mounted in the card-receiving pocket when the envelope is slit along the weakened line, and providing adhesive on the inner face of the envelope for closing the pocket to prevent the removal of a card mounted therein when the envelope is sealed.

This and other objects of the invention will be more clearly understood from the following detailed description and accompanying drawings.

Figure 1 is a top plan view of one type of envelope that might be used in constructing the mailing device;

Figure 2 is a bottom plan view showing the closing flap provided with cut-away portions;

Figure 3 is a bottom plan view of the envelope open, showing the card-receiving pocket mounted thereon;

Figure 4 is a section along the line 4—4, Figure 3;

Figure 5 is a plan view of the type of

card that might be used in the mailing device.

Referring to the above-mentioned drawings, an envelope 10 of any ordinary type, including a body portion 11 and a closing flap 12, is shown. Mounted on the inner face of the flap 12 is a pocket 13. This pocket consists of a rectangular sheet of paper 14 attached to the inner face of the envelope flap by means of an adhesive, as shown at 19. A weakened line 15 extending across the mouth of the pocket 13 is formed in the envelope flap. This weakened line may be formed by making a line of perforations in the envelope flap. A card 18, similar to the one shown in Figure 5, is mounted in the pocket 13. In order to provide access to the card for gripping it to withdraw it a portion of the envelope is cut away, as shown at 16, exposing the edge of the card 18. A portion of the rectangular sheet of paper 14 attached to the envelope flap to form a pocket is cut away at 17 so that the card 18 may be easily gripped without gripping the sheet of paper 14. Adhesive, as shown at 20, is provided on the inner face of the envelope flap so that when the envelope is sealed the mouth of the pocket 13 is closed, preventing the removal of the card 18 from the pocket.

In using a mailing device of this type, a return card 18 provided with a space for the address and a space for the signature of the receiver, stamped and ready for mailing, is mounted in the pocket 13. The mail to be registered is contained in the envelope body 11. When the envelope is sealed the adhesive shown at 20 on the inner face of the flap attaches the envelope flap to the body of the envelope so as to close the pocket 13. When the registered mail is received the receiver slits the envelope flap along the weakened line 15 and withdraws the card 18, which he signs and returns to the letter carrier. A device of this type would eliminate the necessity of the mail carrier carrying a receipt to be signed by the receiver. In this way the work of preparing receipts to be signed by the receivers of registered mail would be eliminated, cutting down the work of the postoffice staff. It would also make it possible for those receiving registered letters to immediately reply, acknowledging the receipt of the same.

I would state in conclusion that while the

2
illustrated example constitutes a practical embodiment of my invention I do not limit myself strictly to the exact details herein illustrated, since manifestly the same can be considerably varied without departing from the spirit of the invention as defined in the appended claim.

I claim.

10 The combination with an envelope and a closing flap thereon, of a rectangular sheet having its sides and one end wall folded

inwardly and secured to the inner face of the flap, forming a card-receiving pocket open at one end, said flap having a fragile line extending across the open end of the pocket and said flap having an opening therein, and said sheet having a recess in one end registering with the opening whereby a finger-receiving entrance is provided to permit access to the contents of the pocket.

VERNON A. CONKLIN.
